WITNESS:

UNITED STATES PATENT OFFICE.

ARTHOR LEE PINKARD, OF YOUNGSTOWN, OHIO.

SWIMMING DEVICE.

Application filed August 9, 1922. Serial No. 580,745.

To all whom it may concern:

Be it known that I, ARTHOR LEE PINKARD, a citizen of the United States, residing at Youngstown, in the county of Mahoning and 5 State of Ohio, have invented new and useful Improvements in Swimming Devices, of which the following is a specification.

This invention relates to swimming devices and has for an object the provision 10 of means whereby a person or persons may be supported upon the water.

Another object is the provision of a swimming device which is provided with manually operated propelling means, which is 15 designed to be operated by the feet of the occupant, adjustable means being provided whereby the occupant of the device may assume either a sitting or reclining position.

20 With the above and other objects in view, the invention further includes the following novel features and details of construction, to be hereinafter more fully described, illustrated in the accompanying drawings 25 and pointed out in the appended claims.

In the drawings:—

Figure 1 is a top plan view of a swimming device constructed in accordance with the invention.

30 Figure 2 is a side view of the same.

Figure 3 is a fragmentary section showing a part of the driving mechanism.

Figure 4 is a section on the line 4—4 of 35 Figure 2.

Figure 5 is a section on the line 5—5 of Figure 4.

Figure 6 is a detail view taken substantially on the line 6—6 of Figure 1.

Figure 7 is a sectional view on the line 40 7—7 of Figure 1.

Referring in detail to the drawings, wherein like characters of reference denote corresponding parts, the invention is shown as comprising a frame 10 which includes a substantially central restricted portion and a forward relatively wide portion, the latter comprising forwardly and outwardly flared side bars 11 and forwardly and inwardly projecting side bars 12, the latter meeting at their forward ends so as to provide a point 13, whereby resistance to the forward movement of the device will be reduced. The frame further includes a transverse strengthening bar 13' and rearwardly and outwardly flared side bars 14

50 which are connected at their rear ends by a transverse bar 15. This last named bar and the meeting ends of the bars 11 and 14, which forms the restricted portion of the frame are connected by a supplemental frame 16, which provides a support for a propelling mechanism which will be later described.

Connected upon opposite sides of the forward portion of the frame 10 by means of bands or similar elements 17, are pneumatic floats 18. These floats are provided with suitable valves whereby they may be inflated. A pneumatic float 19 is also located between the converging forward ends of the bars 12. In addition to the floats 18 and 19, the frame is further provided with floats 20 which are connected to the bars 14 by means of bands or similar elements 21 and like the floats 18 are provided with valves, 75 whereby they may be inflated.

Pivots mounted upon trunnions 22 is a seat 23, which carries a back 24. This seat is capable of pivotal movement so that it may be adjusted to the position of the occupant, whereby the latter may sit in an upright position or may occupy a reclining position. The seat 23 is held in adjusted position by means indicated at 25.

Extending forwardly of the seat and connected to the cross bar 13 is a stomach support 26, so that the occupant of the device may assume a reclining posture, in which position the seat may be tilted to the required angle to provide for the comfort of 90 the occupant.

Extending downwardly beneath the seat 23 is a standard or bracket 27 and mounted in suitable bearings in the lower end of this standard or bracket is a crank shaft 28 which has connected thereto at each end a crank 29 designed to be operated by the feet of the occupant. Mounted upon the crank shaft 28 is a gear wheel 30 and engaging this wheel and mounted upon a longitudinally disposed shaft 31 is a pinion 32. The shaft 31 is geared to a propeller shaft 33, as indicated at 34 and this last mentioned shaft carries a propeller 35, which is designed to be operated by the operation of 105 the foot pedals 29.

Extending from the rear end of the frame 10 and carried by the side bars 14 are spaced rudders 36. Each of these rudders has connected thereto one end of a cable 37, whose opposite end is connected to an operating lever 38, the latter being positioned within 110

convenient reach of the occupant of the device, whereby the direction of travel of the device may be controlled.

The invention is susceptible of various changes in its form, proportions and minor details of construction and the right is herein reserved to make such changes as properly fall within the scope of the appended claims.

10 Having described the invention what is claimed is:—

1. A swimming device embodying a frame including a substantially centrally located restricted portion, a relatively wide forward portion having a pointed end and an outwardly flared rear portion, floats secured to the opposite sides of the frame in front of and at the rear of the restricted portion,

a seat located at the restricted portion, a rudder, means for controlling the rudder, a 20 propeller and means whereby the propeller may be operated.

2. A swimming device embodying a float supported frame, a substantially horizontally disposed stomach support, a seat 25 mounted for pivotal movement adjacent one end of the support and capable of adjustment substantially at right angles thereto, a propeller and foot operated means carried by the frame and operatively connected to 30 the propeller, whereby the latter may be rotated.

In testimony whereof I affix my signature.

ARTHOR LEE PINKARD.
